D. W. BROWN

BUILDING CONSTRUCTION

Filed Nov. 19, 1923

UNITED STATES PATENT OFFICE.

DAVID WALLER BROWN, OF AKRON, NEW YORK.

BUILDING CONSTRUCTION.

Application filed November 19, 1923. Serial No. 675,737.

This invention relates to a building construction and more particularly to floor bases and roof decks which are formed of a plurality of continuous slabs or beams of 5 plastic material, such as calcined gypsum and other cementitious material.

An object of my invention is to provide a monolithic floor or roof which comprises a plurality of reenforced precast slabs or 10 beams so formed that they can be bonded together chemically and mechanically by poured in place cementitious material to form a strong, stiff structure adapted to sustain the loads to which such structures are 15 subjected.

Another object of my invention is to provide a structure which includes a plurality of preformed slabs or beams having reenforcing members arranged and embedded 20 therein to most effectively resist maximum and varying moments and shear, when said reenforcing members in adjacent slabs are united in a continuous structure.

Another object of my invention is to provide a continuous structure comprising a plurality of preformed slabs or beams having a plurality of recesses in the ends thereof, whereby reinforced poured in place cementitious material can be made to form a 30 longitudinal lock between the adjacent ends of mating beams or slabs.

Another object of my invention resides in providing links which are adjustable, for connecting the ends of mating reenforcing 35 members of adjacent slabs or beams to bring the same under tension to form a continuous beam or slab structure.

These and other objects, and the invention itself will appear in the following specification, reference being had to the accompanying drawing, forming a part hereof, wherein:—

Fig. 1 is a plan view of a portion of a floor base or roof deck assembled upon structural beams and partially in section to show the reinforcing elements;

Fig. 2 is a longitudinal sectional view taken on line 2—2 of Fig. 1;

Fig. 3 is a similar sectional view taken 50 on line 3—3 of Fig. 1;

Fig. 4 is a transverse sectional view taken on line 4—4 of Fig. 1; and

Fig. 5 is an enlarged plan view of one of the adjustable links connecting the ends of 55 reinforcing rods embedded in adjacent precast beams or slabs.

Referring to the drawings by characters of reference, in which I have shown a sufficient portion of a floor base or roof deck to enable the invention to be understood, 10 in- 60 dicates precast reinforced beams or slabs which are formed of calcined gypsum or other cementitious material. The slabs are cast with spaced apertures 11 of desired shape, shown herein as circular, which ex- 65 tend longitudinally therethrough, and with ends rabbeted transversely near the top providing end portions 12 which are thinner than the body of the slab. Longitudinal tongues 13 are formed as a portion of the 70 base and sides of the slabs and an angular groove 14 extends longitudinally in each side wall of the slabs, above the tongues 13.

A plurality of reinforcing elements 15, such as steel wire or special or plane metal 75 rods, are embedded within each slab and are positioned between the apertures 11. These rods extend substantially longitudinally through the slabs having their ends bent upwardly from the top and short of the ends 80 of the reduced ends 12. The central portions of the rods extend parallel with and near the base of the slabs substantially one-half the length thereof though midspan portions are bent to deflect upwardly at sub- 85 stantially 45°, extending parallel with the top surface and just below the top surfaces of the end portions of the slab substantially one quarter of the length of the slabs at each end. The extreme ends 32 of the reinforcing 90 members are bent upwardly from the top of the reduced ends 12 of the slab, short of the ends thereof, and these upstanding ends 32 are preferably within the space below the extended top surface of the slab. 95 This arrangement of the rods effectively resists the stresses which are caused by maximum positive and maximum negative bending moment and shear to which the slabs may be subjected.

The slabs 10 are formed in such lengths that the ends thereof will rest upon substantially one half of the top of the flanges of parallel structural floor beams or roof purlins 16, the slabs being assembled in longitudinal and contiguous rows. The mating ends of adjacent slabs are each initially secured together by adjustable links 17, which rigidly connect the aligned upstanding ends 32 of the reinforcing rods 15, securing them 105 together under tension. The links 17 are preferably in the form of apertured metal 110

plates, the inner contour being trapezoidal in shape, the divergent sides 18 being plain, corrugated or roughened.

It will be seen that these links are adjustable transversely and the diverging walls permit the reinforcing rods to be placed under tension when the space between the ends of the slabs vary, as is quite often found to be the case due to irregularities in the fabrication and erection of supporting structure. The ends 32 of the rods 15 project up through the apertures in the links and are bent back over the diverging walls toward the body of the slabs which they reinforce.

15 The preformed slabs with the upstanding ends of the reinforcing members adjacent the ends thereof are assembled end to end in longitudinal rows. The end slab of each of the rows is secured in final position upon 20 the structural beams, and the links 17 are placed over the upstanding ends 32 of reinforcing members either before or after the slab is so positioned. The next slab is then 25 aligned longitudinally with the end slab and the remote end may be elevated permitting 30 the links 17, which have been placed over the upstanding ends of the reinforcing members of the first slab, to be adjusted so that the diverging sides will snugly engage the 35 adjacent upstanding ends of the reinforcing members of both slabs, when the second slab is lowered into position upon the structural beams. When it is necessary or desirable, 40 one or more of the slabs may be laid in position and the adjacent upstanding ends 32 of the reinforcing members may be fastened together by the links, without tilting the slabs. This result is obtained by placing the links over mating upstanding ends of the 45 reinforcing members of adjacent slabs and forcing the links transversely so that the converging inner walls will draw the end portions of the reinforcing rods together, effecting the desired initial tension therein. This 50 last method of joining the reinforcing members of adjacent slabs may also be used to increase or reduce the tension created by that first described after the slabs are substantially in final position.

55 The manner of securing the ends of the reinforcing members together increases the stiffness and strength of a continuous floor or roof formed of slabs since it provides a continuity of action of adjacent slabs, with material reduction in maximum stresses to be resisted.

60 After several contiguous longitudinal rows of the slabs are assembled together by the links, the spaces above the abutting reduced ends and tongued and grooved sides are filled with plastic calcined gypsum 19, or other cementitious material, by filling the spaces until flush with the top surface of the slabs, the hardening of which mechanically and 65 chemically locks the slabs together in a

monolithic structure. Prior to pouring in the cementitious material 19, rods 20 are placed in the adjacent ends of aligned apertures in the slabs extending across the joint between the ends of adjacent slabs and sufficient quantity of the cementitious material 19 is poured into the space above the reduced ends of adjacent slabs to fill the ends of the apertures and the space above the reduced ends embedding the rods 20 therein. 70 If necessary the top walls of the reduced ends above the apertures 11 can be broken to permit the material 19 to be formed into the ends of the apertures, and suitable means such as plastic balls or paper wadding 33 are 75 provided to prevent the plastic material from flowing beyond desired limits within the apertures. Thus it will be seen that the poured in place material fills the grooves in the side walls of the slabs, the space above the side tongues, adjacent ends of the apertures in the slabs and the spaces above the reduced ends of the slabs, thereby bonding the slabs together chemically and mechanically, both longitudinally and transversely 80 and forming a smooth continuous floor or deck.

85 The end slabs of each longitudinal row are secured to the structural beams and serve as an anchorage for the other slabs intermediate thereof. In these end slabs the reinforcing members 15 are continued to the outer end of the same and such end is formed the same thickness as the body of the slab. These end slabs are formed so that they may 90 be assembled at either end of a row, and the intermediate slabs are formed so that they are reversible end to end. The outer end of the end slab is formed with a metal bar 21 embedded therein and extending transversely thereacross. Such bar being bent so that it will pass over the side apertures and under the central apertures. This slab is also formed with a recess 22 in the bottom portion thereof beneath the bar, and an opening 23 through the base beneath the central aperture 11 and adjacent the recess 22 at one side of the bar, to receive an S-shaped retaining clip 24. One end of the S-shaped clip is inserted through the opening 23 and hooks 115 over the bar 21, the central portion resting upon the top flange of the structural beam when the slab is placed in position to be anchored, and the lower end of the clip hooks under the top flange of the structural beam. 120 The longitudinal reinforcing members in the end slabs are bent to engage the transverse bar 21 aligning the bar and the reinforcing members while forming the slab. The reinforcing member extending to the outer ends 125 of the end slabs provides a reinforced overhang thereby strengthening the projecting ends of the roof decks and floor bases.

130 The slabs and poured in place cementitious material therebetween provide a monolithic

effect which is strong, stiff and especially desirable for continuous floor bases and roof decks. The continuous reenforced construction described gives a maximum strength 5 proportionate to the material used, as the metal reenforcements are so placed as to resist most effectively the varying bending moments and shear, and the ends and sides of the precast slabs are so formed and secured together as to effect an adhesive bond 10 and a mechanical locking together of the slabs securing cooperative action to sustain both the dead and live loads.

Various changes may be made in the detailed construction described without departing 15 from the spirit of my invention and the scope of the claims.

What I claim is:—

1. In a building construction, in combination, a plurality of precast slabs of cementitious material provided with reduced ends which cooperate to form a continuous bottom wall, the ends of said slabs having aligned 20 apertures therein; poured in place cementitious material extending into said apertures and also filling the space above said reduced ends; and reenforcing members imbedded in the poured in place material and extending from the apertures in the ends of one slab 25 into the aligned apertures in the end of the adjacent slab.

2. In a building construction, in combination, a plurality of preformed slabs provided with reduced ends forming a continuous bottom wall, said slabs having a plurality of 30 spaced reenforcing members extending substantially therethrough and bent upwardly short of the ends thereof, apertured links having opposite diverging inner side walls 35 over which the ends of said reenforcing members of adjacent slabs are bent to secure the reenforcing members in tension.

3. In a building construction, in combination, a plurality of preformed slabs provided 40 with reduced ends forming a continuous bottom wall, said slabs having a plurality of spaced reenforcing members extending substantially therethrough and bent upwardly adjacent the ends thereof, apertured links having opposite diverging roughened inner side 45 walls, the ends of the reenforcing members extending through the apertured links and being bent over the roughened walls to unite them in desired tension.

5. In a continuous slab or beam construction, in combination, a plurality of preformed slabs having tongues extending from the sides thereof and reduced ends which are assembled to provide a continuous bottom 50 wall, said slabs having metal reenforcing rods extending longitudinally and substantially the length thereof and projecting upward short of the ends thereof; a plurality of adjustable metal links by which the ends 55 of mating reenforcing rods in adjacent slabs

can be secured together, to effect take up of said rods when the distance between the upturned ends thereof vary; and a cementitious poured in place material for filling the spaces between adjacent slabs above said 70 bottom tongues and reduced ends embedding said locking links and bonding said slabs together.

5. A reenforced slab for building construction comprising a body formed of calcined gypsum, having spaced apertures extending longitudinally therethrough, and a plurality of longitudinally extending reenforced members embedded within said body, on each side of the apertures, the ends and 75 central portion of said reenforcing members lying in different planes within the body of the slab.

6. In a continuous slab or beam construction, in combination, a plurality of longitudinally apertured preformed calcined gypsum slabs or beams provided with tongues extending from the sides thereof and grooves in the side walls above said tongues and having reduced ends, said slabs having metal 80 reenforcing rods extending longitudinally and substantially the length thereof and projecting upward short of the ends thereof; a plurality of adjustable metal links for connecting and tensioning the ends of mating 85 reenforcing rods in adjacent slabs to effect the takeup of said rods; and poured in place plastic calcined gypsum for filling the spaces between the adjacent slabs above said side tongues and reduced ends and the ends of the adjacent apertures bonding said slabs together longitudinally and laterally, said locking links being embedded in said poured 90 in place gypsum.

7. In a building construction, in combination, a preformed slab having apertures extending longitudinally therethrough, a bent reinforcing bar near one end of said slab a support for said slab, and an anchoring member engaging said reinforcing bar and 100 said support to couple said slab and said support together.

8. In a building construction, in combination, a preformed slab having apertures extending longitudinally therethrough, a bent 105 reinforcing bar near one end of said slab, extending transversely beneath the central apertures and upwardly adjacent thereto and over the adjacent apertures, a support for said slab, and an anchoring member 110 having hooked ends, one of said ends engaging said bar and the other of said ends engaging said support to couple said slab to said support.

9. In a building construction, in combination, a preformed slab having apertures extending longitudinally therethrough, a bent reinforcing bar near one end of said slab extending transversely beneath the central 125 apertures and upwardly adjacent thereto 130

- and over the adjacent apertures, a support for said slab, and an S-shaped anchoring member, the upper end of said S-shaped member engaging said bar and the lower end 5 of said S-shaped member engaging said support to couple said slab to said support, said slab having a slot formed in the bottom wall thereof to permit the insertion of said S-shaped member to engage said bar.
- 10 10. In a building construction, in combination, a plurality of preformed slabs provided with reduced ends forming a continuous bottom wall, said slabs having a plurality of spaced reinforcing members extending substantially therethrough, and bent 15 upwardly from the top surfaces of said re-

duced ends short of the ends of the slabs, apertured links through which the upturned ends of said reinforcing members extend, said links having opposite roughened side 20 walls, the ends of the said members being bent back over the sides of said links and engaging said roughened side walls, and connecting aligned members in adjacent slabs, and a cementitious poured in place material 25 for bonding the ends of adjacent slabs together.

In testimony whereof I have hereunto affixed my signature this 14 day of November, 1923.

DAVID WALLER BROWN.
